CABINET HEATER

George E. Pickup, Newark, Ohio, assignor, by
mesne assignments, to Florence-Wehrle Stove
Co., Newark, Ohio, a corporation of Ohio

Application June 15, 1934, Serial No. 730,712

3 Claims. (Cl. 126—67)

This invention relates to improvements in heating stoves and is more particularly concerned with cabinet type heaters which are used to condition the air in habitable enclosures such as 5 rooms in houses and schools, or halls, stores, or the like where it is desirable to have an efficient conditioning unit which is conveniently regulated and of pleasing appearance.

It is therefore an object of this invention to 10 provide a cabinet heater which is compactly and simply constructed, which is efficient in operation to secure balanced air conditioning and which is characterized by aesthetic qualities of high order.

Another object is to provide a cabinet heater 15 having air conditioning instrumentalities including humidity apparatus and devices for heat control and in which improved associated means are provided in combination with the instrumentalities for placing the latter in proper relative 20 operative condition to obtain the desired results.

Another object is to provide in a cabinet heater a plurality of air conditioning instrumentalities operatively associated with the combustion unit 25 and having associated indicating means grouped in proximate relation upon a face of the cabinet whereby the operator may ascertain at a glance whether the instrumentalities are in proper operative condition to produce the desired results; and also to provide means allied with the indicating 30 means through which the operator may with ease and assurance maintain the instrumentalities in proper operative condition at all times.

Another object is to provide improved means 35 for controlling each of the air conditioning instrumentalities from a defined localized area of one face of the heater cabinet although the instrumentalities of necessity may be associated with various parts of the heater remote from the said localized area.

40 Other objects and advantages of the invention will be apparent from the following detailed description taken in connection with the accompanying drawing, and in which:—

Fig. 1 is a front elevation of the heater partly 45 in vertical section to show details of the construction.

Fig. 2 is a transverse vertical sectional elevation 50 of the heater taken substantially on line 2—2 of Fig. 1.

Fig. 3 is a sectional plan view taken substantially on line 3—3 of Fig. 1.

Fig. 4 is a perspective view of a control-handle manipulating key.

Generally stated the heater includes a combustion unit supported on a suitable stand and hav-

ing a surrounding cabinet enclosure which is provided at a convenient place, such as in the upper part of the front wall, with a control panel from which air conditioning instrumentalities, operatively associated with the combustion unit and including humidity apparatus and devices for heat control, are maintained in operative condition. This arrangement tends to increase the efficiency of the heater in that the operator will not through oversight or inexperience fail to observe the necessity for ascertaining the operative condition of each of the various instrumentalities to obtain the most efficient heating relationship. The provision of means on the control panel in association with each of the aforesaid instrumentalities to visually indicate its present condition further simplifies operation and increases the efficiency of the heater. This construction and arrangement constitutes a substantial improvement over prior constructions where regulation can only be effected at various isolated and necessarily scattered portions of the heater, with a resulting tendency to fail to maintain the air conditioning instrumentalities in proper operative condition in order to secure the desired effect from the heater, whereby fuel waste and overheating results and the healthful conditions of the surrounding air are impaired.

Referring to the drawing, which shows an exemplary embodiment of the invention, the combustion unit comprises a suitable base member 10 supporting an ash chamber 12 upon which is carried the fire pot 13 of the stove. A combustion chamber 14 is suitably fastened to the fire pot 13 and has an access door 15 in one face.

A cabinet enclosure surrounds the stove and is supported on the base 10. The cabinet may comprise side plates 17 and 18 of sheet metal and a rear plate 19 similarly of sheet metal and having flanges 20 at opposite vertical edges to 40 which the rear edges of the side plates are secured. Where desired, of course, the rear and side plates may all be made of one sheet of metal bent to the desired angular shape or they may consist of suitable castings. The front of 45 the cabinet preferably comprises a cast metal member 21 having rearwardly extending flanges 22 along its vertical edges abutting against and secured to inturned flanges 23 along the forward vertical edges of plates 17 and 18. The member 21 may be formed as one piece or may be cast 50 in a plurality of parts which are fitted together in the structure. A cast metal top member 24 is secured to rear plate 19 and side plates 17 and 18 by suitably attaching depending flanges 25 to 55

the upper part 26 on said plates. The front member 21 and the top 24 may be provided with suitable apertures as desired so as to permit circulation of convection currents of air through the 5 stove.

Incidental to proper conditioning of the air, air conditioning instrumentalities including devices for heat control are provided in association with the combustion unit. Thus, there is provided a suitable draft opening in the upper part 10 of the ash chamber 12 adjacent the bottom of the fire pot 13, and a draft damper 27 is hingedly connected to cover the opening. A hot blast tube 28 extends from the top of the combustion chamber 14 substantially inwardly toward the fire pot, 15 and a damper plate 29 is hingedly positioned on top of the chamber to close the opening to the hot blast tube. A flue 30 is connected to the rear of the chamber 14 and extends through the rear plate 19 to connect with a flue vent. A check damper 31 is hingedly carried by the flue 30 for a well known purpose.

Heretofore, it has been customary to provide means adjacent the controls themselves to regulate the various described controls. But, due to carelessness or inexperience on the part of the operator, the proper relative adjustment of the controls was often neglected and consequently large amounts of fuel were needlessly wasted 30 through inefficient operation. In order to have the most comfortable condition within a room it is necessary to maintain a balanced ratio between the heat production and the prevailing atmospheric temperature conditions.

35 By the present invention, means are provided whereby regulation of all the various controls is conducted from a given centralized area of one face of the cabinet even though some of the controls may be fairly remote from the said area. To this end, a control panel 33 is provided as a part of the described cabinet enclosure, preferably as an inwardly offset portion of the front member 21. This panel 33 may be formed as an integral part of the front 21 or 40 may be a separate unit attached thereto in any suitable manner. Associated means for regulating the various controls to maintain the same in proper operative condition are carried by the panel and will now be described.

50 The draft damper 27 is provided with a laterally extending rigidly secured rod 34 to the end of which there is pivotally connected a substantially vertically extending link 35. The upper end of the link 35 is pivotally attached to the 55 end of an arm 36 by any suitable means, such as a pin or bolt connection 35a. The opposite end of the arm 36 is rigidly secured to a rod 37 extending through the panel 33 for rotary movement and having rigidly secured to its outer end 60 suitable means such as a handle 38 for operating the same. By turning the handle 38 and the rod 37 clockwise as viewed in Fig. 1, the outer end of the arm 36 is raised to impart upward movement to the link 35 which in turn will 65 lift the rod 34 and the attached draft damper 27 to open the same.

70 The check damper 31 may be similarly operated through a handle 39 attached to a rotatable rod 40 extending through the panel 33 to the back of the stove and supported at its inner end by a bracket 41 attached to the upper surface of the flue 30. The inner end of the rod 40 is rigidly secured to an arm 42 pivotally connected to one end of a link 43. The link 43 is pivotally 75 connected at its other end to a rod 45 which is

attached at the freely movable edge of the damper 31. By turning the handle 39 and rod 40 in a clockwise direction as viewed in Fig. 1, the arm is moved in a similar direction to cause the link 43 to carry the rod 45 and the edge of the 5 damper 31 to the right to open the damper.

A similar link arrangement is associated with the hot blast damper 29 for operating the same. A handle 47 is connected to the outer end of a rotatable rod 48 which projects through the panel 10 33 and has an arm 50 rigidly connected to its inner end and adapted for rotation therewith. The other end of the arm 50 is pivotally connected to one end of a link 51 which in turn is pivotally connected at its opposite end to a rod 15 52 attached at the free end of the damper 29. A clockwise movement of the handle 47 will carry the arm 50 and link 51 upwardly to open the damper 29 and permit air to be drawn into the tube 28 for operation of the hot blast. 20

In order to secure accurate adjustment of the above mentioned heat controls and to insure that the same will be maintained in the desired position, friction means are provided to maintain the controls in any position to which they may 25 be adjusted by actuation of the respective handles. The friction means are preferably of similar construction throughout and may comprise springs 54 axially disposed about rods 37, 40 and 48 and bearing against abutment plates 55 which 30 are retained in spaced relation to the panel 33 by pins 56. Washers 57 bear against the face of the panel 33 and serve as bearings for the ends of the springs 54. Spacers 58 which may 35 be in the form of washers or comprise part of the handles themselves are interposed between the handles 38, 39 and 47 and the outer face of the panel 33 and facilitate manipulation of the handles. The springs 54 are maintained under sufficient compression to maintain substantial 40 frictional contact between the handles and the panel 33 in order to counteract the tendency of the various dampers to close through force of gravity, until the handles are urged positively 45 counter-clockwise to cause the dampers to assume their closed positions. Simplicity of operation is secured by the provision of the similarly manipulated regulating means in association with each of the heat control devices.

50 Each of handles 38, 39 and 47 is preferably of a similar uniform construction and is provided with an indicator such as a pointer 59, or other suitable means, cooperating with a series of calibrations 60 or the like on the adjacent panel surface to visually indicate the then operative condition of the controls which is determined by the position of the handles. The operator's judgment as to the extent to which any damper is open at any given time is thereby eliminated and the exact condition of the control device always 60 ascertainable. By supplying simple instructions as to the proper relationship of the various indicators for given effects, efficient operation of the stove by inexperienced persons is possible. The uniform arrangement of the handles and indicators on the panel, as seen in Fig. 1, lends a 65 harmonious and pleasing appearance to the structure.

70 Greatest heating efficiency is attained by maintaining the atmosphere within the room at the proper humidity. This is due to the fact that the actual temperature will not have to be maintained at an excessive degree in order to secure a comfortable condition. Proper atmospheric humidity is likewise an aid to health. Another 75

air conditioning instrumentality in the improved cabinet heater of this invention, therefore, consists of humidity apparatus. In the illustrated example, this comprises a water container 62 supported by a suitable bracket 63 on the rear wall 19 of the cabinet and in operative association with the combustion chamber 14, so that the container will be heated to cause evaporation of water contained therein.

Heretofore, the maintenance of the humidifier in proper operative condition has depended largely upon the experience and discretion of the operator of the stove. The amount of water in the container was largely a matter of guess work, and through carelessness or inadvertence the container was often allowed to remain dry. In consequence fuel was wasted because the air necessarily had to be excessively heated to secure any degree of comfort, and health was impaired due to the abnormal dryness induced by the faulty operation. The present invention overcomes these objections through the provision of an indicator forming part of the apparatus and preferably included as part of the control panel 33 in conjunction with the hereinbefore described indicators of the heat control devices.

Means for operating the indicator may include a float 64 to which is attached an upwardly extending float rod 65. A supporting bracket 66 is secured to the top of the chamber 14 of the stove and is provided with a fulcrum bearing 67 carrying an angularly bent portion of a fulcrum lever 68. One end of the lever 68 is pivotally connected to the float rod 65, and the other end of the lever 68 extends through a slot 69 in the panel 33 and has an indicator finger 70. A suitably calibrated gauge may be provided adjacent the slot 69 so that the position of the finger 70 will indicate the amount of water in the container 62 as the float 64 is carried down by evaporation of the water. Downward movement of the rod 65 will pull the connected end of the lever 68 downwardly whereby the lever will pivot in the fulcrum bearing 67 to raise the opposite end of the lever and concordantly vary the position of the finger 70 which thus shows the amount of water remaining in the container and calls the operator's attention to the need for refilling the same.

In order to maintain the humidifier in proper operative condition means are provided adjacent the indicator 70 for conveniently filling the container 62. Means for conveying water, such as an inclined trough 71, is attached at one end to the container by a suitable angle bracket 72, and at its end the trough is connected by means of an angle bracket 73 to the lower edge of the panel 33. A guide 73a for the float rod 65 may be secured to the end of trough 71 and prevents surface tension of the water in the container 62 from forcing the float 64 to the side of the container. A funnel-shaped member 74 is provided behind the panel 33 and is pivotally supported at the edge of an aperture 75 therein by means of a hinge connection 76. A door 77 having a handle 78 is connected by means of a bracket 79 to the funnel 74 and covers the aperture 75. When the door 77 is pulled outwardly the flaring upper part of the funnel will be exposed and water may be poured therethrough into the trough which conveys the liquid to the reservoir 62 for maintaining this air conditioning instrumentality in proper operative condition.

By arranging all of the means for maintaining the air conditioning instrumentalities in proper

operative condition at a common locality on the cabinet enclosure, as provided by the panel 33, the operator has, within narrow limits and conveniently accessible, the controls necessary to procure the most effective results from the stove 5 for any desired heating ratio. Moreover, the relative adjustment or condition of every control is ascertainable at a glance.

A closure member 80 is preferably arranged flush with the front member 21 to enclose the panel 33 and the means carried thereby in order to render the cabinet enclosure of generally uniform and pleasing appearance. Suitable means such as hinge lugs 81 (Fig. 3) may be secured to the bottom of member 80 and fit into apertures 82 formed below panel 33. A flange 83 is preferably formed at the upper edge of member 80 and fits into an offset portion forming a seat 84 at the edge of top member 24. A manually engageable portion 85 at the upper corner of the member 80 facilitates manipulation of the member. The member 80 is swung outwardly to the dotted line position in Fig. 2 to gain access to the panel, and may readily be entirely removed if desired.

Before the stove has reached any degree of heat, the handles 38, 39 and 47 may be manipulated by the hand of the operator. However, after the stove has been in operation for some time, the handles may become too hot to be touched. It is therefore desirable to provide means whereby the handles may be manipulated so that the operator will not burn himself. An exemplary manner of accomplishing this comprises forming the handles in bar shape, and providing a key 87 (Fig. 4) 35 having a slot 88 formed in its end and adapted to receive a handle for turning the same.

I will state in conclusion, that while the illustrated embodiment of the invention discloses a preferred form, it is to be understood that the same may be considerably modified in detail without departing from the spirit and scope of the appended claims.

I claim as my invention:

1. A cabinet heater comprising, in combination, 45 a combustion unit, a cabinet enclosing said unit in spaced relation to provide an air circulation space thereabout, a humidity tank located near the top of said unit in communication with said circulation space to deliver into the circulating 50 air water vapor generated by heat transmitted from said unit to said tank, one wall of said cabinet including an inwardly recessed portion located above the top of said tank and having an opening therein, a funnel member in communication with said tank mounted to lie normally in an out-of-the-way position behind said recessed portion and being movable forwardly through said opening substantially beyond the front face of said recessed portion to expose the upper end 60 thereof for receiving water for said tank, manually engageable means on said funnel for withdrawing the same, and a removable closure fitting over said recessed portion in concealing relation to said opening and said funnel and having 65 its outer surface substantially flush with said one wall when in closed position.

2. In combination in a cabinet type heater of the character described including a heat unit and an enclosing cabinet in spaced relation thereto 70 providing an air circulation space, a humidity tank located in proximity to said unit to be heated thereby and communicating with said space to deliver water vapor to the air in circulation therethrough, one wall of said cabinet having a 75

panel section in the upper part thereof above the top of said tank, said section having an aperture therein, a funnel member mounted behind said section and being movable through said aperture 5 to receive water for said tank, and a trough sloping from said panel section toward said tank secured at one end to said panel section below said funnel to receive water therefrom and being secured at its opposite end to said tank in position 10 to discharge water thereinto.

3. In a cabinet heater of the character described, the combination of a heat unit having a cabinet surrounding the same in spaced relation laterally and above to provide an air circulation 15 space thereabout, a humidity tank mounted in heat receiving relation near the upper part of said unit and communicating with said space to deliver water vapor to the circulating air, one vertical wall of said cabinet including a panel 20 section above the top of said tank having an opening therein, a water funnel mounted behind

said section for movement through said opening, means for conducting water from said funnel to said tank, said panel section having a vertical slot adjacent to said opening, a lever arm having an indicator at one end projecting through said slot and extending through said space with its opposite end overlying said tank in vertically spaced relation, a bracket mounted upon the upper part of said heating unit and pivotally supporting said arm at a fulcrum point intermediate its ends, a link depending from said tank-overlying end of the arm and having a float at its lower end located within said tank and adapted to rise and fall with the changes in water level therein to move said link vertically for causing 15 said arm and said indicator to shift correspondingly, and means for guiding said link in the vertical movements thereof to hold said float against lateral movement into engagement with the wall of the tank. 20

GEORGE E. PICKUP.
